[57] CLAIM

The ornamental design for a facsimile transceiver copying machine, as shown and described.

DESCRIPTION

FIG. 1 is a front, top and right side elevational perspective view of a facsimile transceiver copying machine showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a perspective view in condition that a cover is opened and a paper cassette is pulled.

FIG. 1

FIG. 2

*FIG. 3**FIG. 4**FIG. 5**FIG. 6**FIG. 7**FIG. 8*
